UNITED STATES PATENT OFFICE.

CHARLES P. SALGEE, OF PHILADELPHIA, PENNSYLVANIA.

FLUID ENGINE.

1,427,701.

Specification of Letters Patent. Patented Aug. 29, 1922.

Application filed September 27, 1920. Serial No. 413,010.

To all whom it may concern:

Be it known that I, CHARLES P. SALGEE, a citizen of the United States, residing at Philadelphia, in the county of Philadelphia and State of Pennsylvania, have invented 5 new and useful Improvements in Fluid Engines, of which the following is a specification.

My present invention has reference to a 10 fluid pressure operated engine.

My object is to produce a simple construction of engines of this character in which a simple but novel construction of parts actuated by fluid under pressure influences a 15 piston to impart a continuous reciprocatory movement thereto. A further object is to construct an engine or motor including a casing having an inner member both of which are ported and a slideable valve in the 20 inner casing having heads thereon which divide the said inner casing into an upper and a lower compartment, the said valve having ports which are brought successively into operation by fluid admitted to either the 25 upper or lower chambers, such fluid actuating the plunger for a greater length of travel than the valve so that the ports are brought into proper alignment to receive and to exhaust the fluid, spring means im- 30 parting an initial movement to the plunger, and said plunger carrying a piston which projects through a stuffing box at one end of the casing.

The foregoing, and other objects which 35 will be apparent as the nature of the invention is better understood may be accomplished by a construction, combination and operative arrangement of parts, such as is disclosed by the drawings which accompany 40 and which form part of this application.

In the drawings:—

Figure 1 is an elevation of a fluid pressure engine constructed in accordance with this invention.

Figure 2 is a central vertical longitudinal sectional view through the same.

Figure 3 is a top plan view thereof.

Figure 4 is a sectional view approximately on the line 4—4 of Figure 2.

Figure 5 is a sectional view approximately on the line 5—5 of Figure 2.

Figure 6 is a bottom plan view.

Figure 7 is a vertical section of the valve.

Figure 8 is a perspective view of the plunger.

Figure 9 is a vertical section of the headed

member which carries the cylinder that forms one of the compartments of the casing.

Figure 10 is a similar view of the tubular 60 member that provides the second inner compartment of the casing.

My improved construction of fluid operated engines includes an outer cylindrical casing 1 which is provided, on one of its sides 65 with a longitudinally extending fluid receiving passage 2 that is ported, adjacent to its upper and lower ends, as indicated by the numerals 3 and 4 respectively. These ports 4 can be made by providing the outer wall 70 of the passage with openings and inserting a suitable drill therethrough, after which the openings may be plugged. By providing the casing with such openings, ports in other elements that are included in the 75 improvement may be likewise made.

The tubular casing 1 has its upper or outer end open, the same being closed by a head 5, the gasket 6 resting between the head and the said end of the casing, and securing 80 means, such as bolts 7 passing through openings in the head and received in threaded orifices in the casing. Thus the head compresses the gasket against the casing. The head is centrally provided with an opening 85 that is surrounded by an annular outstanding flange 8 which provides a stuffing box, a suitable stuffing 9 being arranged therein. The stuffing box has exterior threads which are engaged by interior threads on the flange 90 of a cap nut 10.

The casing, at the side thereof opposite that provided with the passage 2 has, adjacent its ends fluid outlet ports 11 and 12 respectively, the same being arranged in 95 alignment with ports 13 and 14 respectively that are formed in the side walls of the tubular members 15 and 16 respectively that provide the inner elements of the casing. The tubular member 15 is integrally formed on 100 the head 5, while the tubular member 16 has a closed end which rests on the rear or closed wall of the casing 1, securing elements 17 passing through the said closed end of the casing and entering the closed end of the 105 tube 16, thus not only securing the tube in the casing, but properly centering the same. In this respect, it should be stated that the elements 7 likewise properly position the tube 15 in the casing, that is the 110 securing means hold both of the casings against turning, and therefore their ports in

proper alignment with the outlet ports 11 and 12. The tube 15 has an inlet port 18 disposed opposite the port 3, and the tube 16 has an inlet port 19 disposed opposite the port 4. By reference to the drawings, it will be seen that a determined space is arranged between the tubes 15 and 16, and in this space there is received an inwardly directed flange 20 provided approximately centrally of a tubular valve 21. The valve 21 is slidable in the casing, being guided between the tubular members 15 and 16 and the casing proper. The valve 21 is held against turning by forming the same with a slot 22 within which is received a pin 23 that passes through the casing 1. The valve has outlet ports 24 and 25 respectively and inlet ports 26 and 27 respectively.

Carried by the closed end of the tube 16 is an inwardly extending pin 28. On the end of this pin there is threaded a headed member 29 which contacts with a washer 30 that is slideable on the said pin 28, being influenced by a spring 31 that surrounds the pin 25 and contacts with the washer and with the closed wall of the tubular member 16.

The inturned flange 20 of the valve 21 has depressions or angle walls which surround the passage therethrough and which provide contact elements or seats 32 and 32' respectively, for the beveled inner surfaces on the heads 33 and 34 of a plunger 35. The heads 33 and 34 may be adjustably secured to the stem which connects the same, the stem being, however, preferably formed on the lower head 34 and having a threaded end which is received in a threaded bore in the inner face of the head 33.

Both of the heads 33 and 34 are preferably provided with annular depressions within which are seated expandable gaskets 36 and 37 respectively, the said gaskets being in contacting engagement with the respective tubes 15 and 16. The head 34 has a depression 38, in the outer face thereof, so that the pin 28 and the headed element on the end thereof may be partly received in the said head 34. The head 33 has secured thereto a piston rod 39 that extends through the packing box at the outer end of the cylinder. The piston rod has its outer end provided with a slotted head 40, and received in the slot is an element 41 which is actuated on the reciprocation of the piston rod. On the piston rod, and contacting with the outer face of the head 33 of the plunger is a buffer spring 42.

Connected in the mouth of the passage 2 is a pipe 43. The passage of this pipe is under the control of a valve 44. The pipe is connected to a fluid supply and the fluid in the supply is under pressure.

Assuming the parts to be in the position illustrated in Figure 2 of the drawings and the valve 44 turned to permit of the passage

of fluid through the pipe 43, it will be seen that the fluid will be admitted into the lower chamber in the casing which, for distinction, is indicated by the numeral 45, below the head 34 of the plunger. The fluid will cause the plunger to be moved in an outward direction until the head 34 contacts with the wall 32 of the flange 20 on the valve 21. When the parts are in the position shown in the said Figure 2 the ports 13, 24 and 11 are in alignment, so that fluid which has been previously let into the upper compartment 46 of the casing will exhaust therethrough. The contacting engagement of the head 34 with the flange 20 will cause the valve to be moved longitudinally, bringing the port 24 of the valve out of alignment with the ports 11 and 13, and also bringing the port 26 in alignment with the ports 3 and 18. The head 30 is, however, of sufficient length to cover these ports so that the spring 42 can be compressed before the plunger is moved to bring the said head 33 to uncover the ports. This movement of the valve, of course, causes the port 27 to be brought out of register with the inlet ports 4 and 19, but the port 25 of the said valve is brought into register with the ports 14 and 12, so that the fluid in the lower compartment 45 will be exhausted through these ports. The fluid now acts on the head 33, causing the plunger to be moved in an opposite direction, and also moving the piston 39 inward of the casing. The head 34 is also of a length to cover the inlet ports 19, 27 and 4, when the plunger has been returned, so that the spring buffer means are contacted by the said head and compressed, and from thence expanded to impart initial movement to the plunger and cause the head 34 thereof to uncover the intake ports.

Suitable washers may be arranged around all of the movable parts to insure fluid tight joints therebetween. The buffer springs carried by the plunger and by the casing are sufficiently strong to overcome any friction which may exist between the stuffing box and piston rod or between the heads of the plunger and the inner sections of the casing formed by the tubular members 15 and 16.

What I claim is:

1. In a fluid pressure engine, a tubular casing having inner tubular members whose confronting ends are disposed away from each other and which divide the interior of the casing into two compartments, the casing and the tubular members having inlet and outlet openings which align, and the casing having a fluid intake passage communicating with its intake ports, a tubular valve arranged for slideable movement between the inner and outer members of the casing and having an inturned flange received between the tubular inner members of the casing, a plunger having oppositely disposed heads

and carrying a piston rod which projects through a packing box in one of the compartments, and the heads of the plunger being in the path of engagement with the 5 flange of the valve whereby the intake and outlet ports of the valve are successively brought into register with the intake and outlet ports of the respective compartments of the casing.

10 2. In a fluid pressure engine, a tubular casing having inner tubular members whose confronting ends are disposed away from each other and which divide the interior of the casing into two compartments, the casing 15 and the tubular members having inlet and outlet openings which align, and the casing having a fluid intake passage communicating with its intake ports, a tubular valve arranged for slidable movement between the 20 inner and outer members of the casing and having an inturned flange received between the tubular inner members of the casing, said valve having intake and outlet ports one of which is normally in alignment with 25 one of the intake ports in the casing in one of the compartments thereof, and the other in alignment with the outlet ports in the second compartment of the casing, a plunger having oppositely disposed heads and 30 carrying a piston rod which projects through a packing box in one of the compartments, and the heads of the plunger being in the path of engagement with the flange of the valve, to move the latter and bring the 35 remaining intake and outlet ports thereof in register with the remaining intake and outlet ports of the casing.

3. In a fluid pressure engine, a tubular casing having inner tubular members whose 40 confronting ends are disposed away from each other and which divide the interior of the casing into two compartments, the casing and the tubular members having inlet and outlet openings which align, and the casing 45 having a fluid intake passage communicating with its intake ports, a tubular valve arranged for slidable movement between the inner and outer members of the casing and having an inturned flange received between 50 the tubular inner members of the casing, said valve having intake and outlet ports one of which is normally in alignment with one of the intake ports in the casing in one of the compartments thereof, and the other 55 in alignment with the outlet ports in the second compartment of the casing, a plunger having oppositely disposed heads and carrying a piston rod which projects through a packing box in one of the compartments, and 60 the heads of the plunger being in the path of engagement with the flange of the valve,

to move the latter and bring the remaining intake and outlet ports thereof in register with the remaining intake and outlet ports of the casing, and buffer means between the ends of the casing and the heads of the plunger. 65

4. In an engine which is operated by fluid under pressure, a casing which includes an outer and an inner tubular member, the 70 inner tubular member being in sections and having their confronting ends spaced, and dividing the casing into spaced compartments, both of said compartments having registering intake and outlet fluid ports, 75 means for delivering fluid under pressure to the fluid intake ports, a cylindrical valve disposed for slidable movement between the inner and outer members of the casing, 80 guide means between the outer member of the casing and the valve for holding the valve from turning in the casing, said valve having intake and outlet ports arranged whereby one of the intake ports will align with the intake ports in one of the compartments of the casing, and the outlet port will align with the outlet ports in the other compartment of the casing, when the fluid is let into the casing through either of the 85 said intake ports of the said casing, and means in the casing influenced by the pressure of steam for moving the ports thereof to such position.

5. In an engine which is operated by fluid under pressure, a casing which includes an 90 outer and an inner tubular member, the inner tubular member being in sections and having their confronting ends spaced, and dividing the casing into spaced compartments, both of said compartments having 95 registering intake and outlet fluid ports, means for delivering fluid under pressure to the fluid intake ports, a cylindrical valve disposed for slidable movement between the inner and outer members of the casing, 100 guide means between the outer member of the casing and the valve for holding the valve from turning in the casing, said valve having intake and outlet ports arranged whereby one of the intake ports will align 105 with the intake ports in one of the compartments of the casing, and the outlet port will align with the outlet ports in the other compartment of the casing, when the fluid is let into the casing through either of the 110 said intake ports of the said casing, and buffer means for imparting initial movement to the last mentioned means and for preventing said last mentioned means contacting with the ends of the casing. 115

In testimony whereof I affix my signature.
CHARLES P. SALGEE.
